UNITED STATES PATENT OFFICE.

EDGAR B. JEWETT, OF BUFFALO, NEW YORK.

IMPROVEMENT IN SLOP-JARS.

Specification forming part of Letters Patent No. 222,405, dated December 9, 1879; application filed November 4, 1879.

To all whom it may concern:

Be it known that I, EDGAR B. JEWETT, of Buffalo, in the county of Erie and State of New York, have invented certain new and useful Improvements on a Slop-Jar; and I do hereby declare that the following description of my said invention, taken in connection with the accompanying sheet of drawings, forms a full, clear, and exact specification, which will enable others skilled in the art to which it appertains to make and use the same.

This invention has special reference to slop-jars; and it consists in the peculiar arrangement of parts and details of construction, as hereinafter first fully set forth and described, and then pointed out in the claim.

In the drawings, Figure 1 is a longitudinal sectional elevation of my improved slop-jar. Fig. 2 is a plan of the same. Fig. 3 is a plan of the blank from which the guard for my jar-cover is obtained.

The object of my present invention is the production of a slop-pail the cover of which shall be provided with a guard, said guard being obtained from a heretofore waste piece, as hereinafter fully specified.

In the manufacture of toilet-ware from tin it is customary to make it in sets consisting of a water-carrier, a bath, and a slop jar or pail. The bath is made from a piece of tin twenty inches by twenty-eight inches in size, the two curved pieces B B forming the sides of said bath. In cutting these two pieces there remains a part, A, which has one straight and one curved edge, it being a segment of a circle, and which part has heretofore been always considered and treated as waste, adding to the cost of manufacture of the bath the price

of removing the waste. This piece A, I propose to turn to useful account by applying it to the cover C of the slop-pail by bending it into circular form and securing it at right angles to the plane of the cover around its periphery, in which case such piece A effectually serves as a guard to prevent water, when being thrown into the pail, from splashing over the same, care being taken that the said water is poured into the pail from that side opposite said guard A. It will thus be seen that in applying the segment A to the cover of the jar, I obtain the double result of, first, utilizing a waste piece, and, second, improving the jar.

By thus making the jar-cover with a projecting rim or guard from a waste piece, as specified, I am enabled to manufacture and sell this jar at the same price as that asked for jars the covers of which are not so provided with a guard, thus giving the public the benefit of my improvement without any expense whatever.

Having thus fully described my improvements, I claim as new and desire to secure to me by Letters Patent—

A slop-jar the cover of which is provided with a guard made from a segment of a circle bent into circular form and secured to the outer edge of said cover, as stated.

In testimony that I claim the foregoing as my invention I have hereto set my hand and affixed my seal in the presence of two subscribing witnesses.

EDGAR B. JEWETT. [L. S.]
